REVOLVING DOOR

James M. Tatman, Cincinnati, Ohio, assignor to
 Van Kannel Revolving Door Company, New
 York, N. Y., a corporation of New Jersey

Application March 4, 1931, Serial No. 519,991.

7 Claims. (Cl. 20—18)

This invention relates to doors and is particularly directed to that type of door known as a revolving door which includes a plurality of wings extending radially from a common axial support 5 and moving within a circular cage having doorways in opposite sides. More specifically, the invention is primarily directed to the apparatus included in the mounting of the wings on the common axial support for permitting collapse of the 10 wings in case of panic where efforts are made to revolve the door in reverse directions simultaneously or in cases where it is desired to fold the wings of the door for clearing the doorway.

It is an object of this invention to provide an 15 improved revolving door of the type above mentioned which includes highly efficient wing release devices at the top or bottom of the axial mounting of the revolving door or both, permitting substantial rotative collapse of the doors under undue 20 strains above the forces required to revolve it for ordinary use and for collapsing the door when it is desired to fully open the passageway and render the door inoperative.

It is another object of this invention to provide 25 devices incorporated in a revolving door for automatically releasing the wings of the door from their normal positions under undue strains which are of a highly improved nature in view of the fact that they fully stabilize the wings in their normal 30 operative positions, will not become inoperative or bind in position and are immediately and sensitively responsive to collapse when rotative pressures over the maximum are exerted.

It is a further object in view of the foregoing 35 to provide that the wings of the revolving door are mounted in their relative positions by means of the automatic release devices in association with other stabilizing means for positively maintaining the parts in assembly after they are collapsed but permitting the doors to be swung against each other into a compact group in the same general radial position whereby the revolving door can be rendered inoperative for traffic through an open doorway.

45 It is still another object of this invention to provide a revolving door in which the features of collapse include the utmost flexibility for arranging the wings of the door when the door is to be rendered inoperative whereby the passage- 50 way can be substantially cleared without dismantling the revolving door from its axial mounting.

Other objects and certain advantages will be more fully apparent from the description of the 55 accompanying drawing, in which:

Figure 1 is a perspective view illustrating a revolving door incorporating the present improvements.

Figure 2 is a sectional view taken on line 2—2, 65 Figure 1, showing the axial mounting construction at the lower end of the revolving door in plan view.

Figure 3 is a sectional view taken on line 3—3, 66 Figure 2, additionally illustrating the details of the door mounting.

Figure 4 is a sectional view taken on line 4—4, 70 Figure 3, detailing the construction and mounting of one of the detents and its attachment within the particular wing of the door.

The invention is herein disclosed as applied to 75 a door having four wings, it being understood however that any number of wings may be provided. The wings of the door are disposed radially from a fixed center or axis and are rigidly but collapsibly supported on a common axial mounting for free revolution. The cage within which the door revolves is of any conventional design as well as the construction of the wings of the door independent of the construction at the point of attachment of the devices of this invention.

80 Preferably, the mechanisms associated with the wings and axial mounting, which provide the safety or collapsing feature for the wings and which release when pressures are exerted against them greater than those required to revolve the door, are provided at the top and bottom of the door respectively. In view of the duplication, only the mechanism at the lower end of the axial mounting of the revolving door is illustrated. The 85 assembly of certain parts of the central axial mounting includes the assembly of parts instrumental for accomplishing the object of this invention.

90 Referring specifically to the drawing, the floor is indicated at 6; the wings of the door at 7, the lower or base mounting for the central axis of the door at 8, the upper mounting at 9 and the cage or doorway at 10.

95 A socket 11 is provided in the floor directly below and concentric with the axis of the door, this 100 socket including a sleeve 12 countersunk into the concrete or flooring. Another sleeve 13 including an upper attaching flange 13^a is attached to the sleeve 12 by means of screws or rivets and depends into the socket. This sleeve has the stationary central shaft 16 of the door attached thereto in a tapered inner bore by means of a cross pin 16^a passing through a slot in the lower end of the central shaft. This central shaft structure is conventional.

The feature of having the entire revolving door assembly removable from its axial position within the cage by shifting the central shaft longitudinally of its axis forms no part of this invention.

5 The parts described for accomplishing this feature have been only included for the purpose of fully describing an axial mounting with which the present release devices are associated.

A disc 14 is provided fixed to the spindle or axial 10 support tube 15 of the door by means of keys 15^a. This disc 14 rests on the upper surface of the sleeve 13 for a rotative bearing and is maintained against lateral shifting on the axial mounting by means of a sleeve 16^b between the sleeve 15 and 15 the shaft 16. The disc 14 is preferably of fabricated structure for convenience of manufacture and assembly of the parts, this however being entirely arbitrary as will be apparent.

Primarily, the disc includes a concentric groove 20 19 in its upper surface, this groove being of considerable depth. In the present case it may be of a depth slightly greater than half the thickness of the disc. The groove is provided with a plurality of vertically disposed tapered apertures 20 which extend entirely through the disc. There 25 is one aperture provided for each wing of the door for receiving the respective locking detents for the particular doors.

Each door includes a vertically movable detent 30 or spring actuated plunger 21. This plunger is slidably mounted within a metal block 22 inserted in a groove 22^a in the lower edge of the wing of the door toward the inner side thereof. The metal block includes a hollow upwardly extended 35 circular lug 22^b housing a compression spring 23 disposed between a shoulder 24 of the detent formed by counterturning the upper end thereof and an inner flange 25 of the lug, the upper end of the counterturned portion of the detent extending 40 through the top of the circular lug for the purpose of additionally guiding the detent over and above that guidance provided by the main body of the detent disposed in the block.

Another metal block or insert 26 is provided 45 above the mentioned block for surrounding the hub, this upper block being secured in position within the groove 22^a of the door by means of the face plates 27 attached to each side of the door. Screws 28 extend through the face plates into the 50 upper block. The lower or detent support block is attached in place by means of heavy screws 29 extending upwardly from the underside thereof into the upper block. The underside of the detent support block engages upon the disc and the detent 55 extends into the groove and when in registry with its particular tapered aperture has its lower or tapered end 30 engaged in the particular aperture.

The block housing the detent also includes an 60 inward extension which has a vertically disposed V-shaped groove 31 on its extreme end, which groove is adapted to engage a particular tooth extension 32 formed radially of a hub portion 33 of the disc. The inner end portion of the lug further includes a downwardly extended lug 34 fitting 65 within a particular groove 35 in the upper face of the disc, this groove providing appropriate clearance disposed in the proper manner for permitting passage of the downward extension outwardly into the concentric groove when that 70 function is required.

Assuming that each wing of the door is in its proper position radially disposed from the central axis of the door, the following action will be 75 observed in case of undue pressure on a particu-

lar wing. If the pressure exerted against the wing of the door is greater than that required to re-volve the door, since the compression spring of the detent is provided of a strength in keeping with the taper of the lower end of the detent which will permit the detent to move upwardly and out of its aperture, the detent will function in this manner and be free to travel in a circular path in the concentric groove. This relases one point of support of the wing with the result that the inner or grooved end of the block rolls on the tooth shaped radial extension of the hub as the detent moves in the groove. After a certain amount of collapsing movement in this manner, the outer lug extension of the door containing the vertical groove will have moved into the lateral extension of its particular groove sufficiently to pass outwardly into the circular track or concentric groove.

The clearance grooves for the downward lug extensions are extended on the outer side of the concentric groove as at 36 to permit the lug to swing slightly beyond the center of the circular track which permits a total collapsing and a full 135° swing of the wing of the door in collapsing movement. It will be observed from the drawing that by this arrangement it is possible to swing the wings of the doors which were formerly disposed at right angles to each other completely around until they are disposed parallel, each passing through 135°. The other two doors which are intermediate these two wings as the collapsing occurs need only move 45° and they are thereupon disposed in parallelism with each other and with the first two wings. Therefore, if it is desired to totally collapse the door, this can be done purposely to provide clear entrance without operation of the door, aligning the four doors into a compact central position which at its fullest or aggregate width is not much greater than the combined thickness of the four wings (see dot and dash lines of Figure 2). Also the door wings may be disposed in pairs radially disposed from opposite sides of the axial mounting 105 in line with the traffic through the doorway.

By the provision of the downward lug and detent, which parts remain in their fixed grooves or tracks after the particular wing has collapsed, the wing still remains as a fixed part of the assembly. For convenience in manufacture, it is possible to make the disc in three parts. A main disc 37 may be provided including a central circular countersunk portion 38 and an upwardly extending hub 39. Another disc 40 may be inserted over the hub and into the countersunk portion for making up the concentric groove and including the clearance grooves for the downwardly disposed lugs in the respective wings. On top of this, a circular toothed element 41 may be mounted surrounding the hub of the plate and aptly described as part of the hub.

The construction of the parts of the central axial mounting of the door extending from the top to bottom thereof for joining the respective 140 mountings may be of any standard construction. It is proposed to join the parts by means of the sleeve or tube 15 keyed to the respective hubs of the upper and lower discs so that they rotate unitarily. Another sleeve 43 may surround the 145 inner sleeve for the purpose of providing an artistic post which will be exposed between the respective wings and which fits into the inner edges of the wings in a manner lending to the general appearance of the door.

Having described my invention, I claim:

1. In a revolving door, a plurality of wings disposed radially from a common axis, a spindle for mounting said doors on the common axis, vertically operating detents mounted in and extending from the lower edges of the doors, a circular plate fixed to the spindle and including a concentric groove in its face adjacent the detents, and a plurality of orifices, one for engagement by each detent for locating the wings in their normal radial operative positions, each of said wings having a vertical groove on its inner edge, said circular plate including a hub having teeth engaging the respective grooves for further maintaining the wings in normal radial operative positions, said plate including grooves, extensions formed on the lower edges of the wings and disposed in said grooves, said grooves providing clearance for the extensions on the wings whereby they move outwardly as the detents move in a circular track after displacement from the orifices for permitting full collapse of the door beyond 90°.
2. In a revolving door, a plurality of wings radially disposed, a spindle with which said wings are revoluble, a plate attached to said spindle, said plate being provided with a guide groove for each wing and an annular groove, said guide grooves communicating with the said annular groove, means depending from each wing for engagement with the said annular groove, and means depending from each wing for engagement with its respective guide groove, said first-mentioned means being adapted to move in said annular groove and said second-mentioned means being adapted to move in said guide grooves and into the said annular groove for guiding the wings in collapsing the door.
3. In a revolving door, a plurality of wings radially disposed, a spindle with which said wings are revoluble, a plate attached to said spindle, said plate being provided with a guide groove for each wing and an annular groove having depressions in the bottom thereof, said guide grooves communicating with the said annular groove, latching means on each of said wings cooperating with said depressions in the bottom of said annular groove for releasably holding said wings in radial positions, and means on each door wing for engagement with its respective guide groove, the said latching means on each wing being adapted to move in said annular groove and the said guide-groove-engaging means being adapted to move in said guide grooves and into the annular groove for guiding the wings in collapsing the door.
4. In a revolving door, a plurality of wings radially disposed, a spindle with which said wings are revoluble, a plate affixed to said spindle, said plate being provided with an annular groove having a plurality of depressions in the bottom thereof, said plate also being provided with a plurality of guide grooves, each of said guide grooves communicating with the said annular groove, a vertically-movable detent mounted in each wing for engagement with the said annular groove and for engagement with said depressions for holding the wings in radial positions, a vertical groove in each wing, teeth carried by the said plate for engagement with the vertical grooves in the wings, and means on the wings for engagement with the guide grooves in the plate, said means moving in said guide grooves and said detents moving in said annular groove when the wings are moved to collapse the door.
5. In a revolving door, a plurality of radially-disposed wings, a spindle with which said wings are revoluble, a plate affixed to said spindle, said plate being provided with a substantially U-shaped guide groove for each wing and an annular groove, said guide grooves communicating at each of their ends with said annular groove, means on each door wing for engagement with said annular groove, and means on each door wing for engagement with its respective guide groove, said first-mentioned means being adapted to move in said annular groove and said second-mentioned means being adapted to move in one leg of each of said guide grooves when the wings are moved in one direction to collapse the door and said second-mentioned means being adapted to move in the other leg of each of said guide grooves when the wings are moved in the opposite direction to collapse the door.
6. In a revolving door, a plurality of radially-disposed wings, a spindle with which said wings are revoluble, a plate affixed to said spindle, said plate being provided with a guide groove for each wing and an annular groove, said guide grooves communicating with the said annular groove on the inner side thereof, said plate also being provided with grooves formed in the outer annular side of the annular groove which align with the ends of the guide grooves, means depending from each wing for engagement with the said annular groove, and means depending from each wing for engagement with its respective guide groove, said first-mentioned means being adapted to move in said annular groove and said second-mentioned means being adapted to move in said guide grooves and into the said annular groove and to engage the grooves in the outer wall of the annular groove for guiding the wings to collapse the door.
7. In a revolving door, a plurality of radially-disposed wings, a spindle with which said wings are revoluble, a plate affixed to said spindle, said plate being provided with a substantially U-shaped guide groove for each wing and an annular groove, said substantially U-shaped guide grooves communicating at each of their ends with said annular groove, said plate also being provided with grooves formed in the outer annular side of the annular groove which align with the ends of the guide grooves, means on each door wing for engagement with said annular groove, and means on each door wing for engagement with its respective guide groove, said first-mentioned means being adapted to move in said annular groove and said second-mentioned means being adapted to move in one leg of each of said guide grooves and to engage the grooves in the outer wall of the annular groove when the wings are moved in one direction to collapse the door and said second-mentioned means being adapted to move in the other leg of each of said guide grooves and to engage the grooves in the outer wall of the annular groove when the wings are moved in the opposite direction to collapse the door.

JAMES M. TATMAN.
